COIN CONTROLLED RELEASE MECHANISM

George W. Dooley, San Bernardino, Calif., assignor to Milton R. Standish, San Bernardino, Calif.

Application February 1, 1939, Serial No. 254,625

8 Claims. (Cl. 194—2)

This invention relates to a coin-controlled release mechanism. This mechanism may be employed for releasing any movable part that is intended to be moved after the insertion of a coin, or coins, in a coin-receiving device. Such release mechanism may be employed for enabling a door, or a drawer, to be opened, or for any other similar purpose. It is also useful for controlling the ejector of a vending machine; and in the present specification the invention is described as applied to a vending machine for vending newspapers.

One of the objects of the invention is to provide a coin-controlled release mechanism, in which the release can be effected by means of a coin of a larger denomination, or by means of coins of a lower denomination; for example, by means of a dime, or by means of two five-cent coins. A release mechanism operating in this way is very desirable because it enables the release mechanism to be operated regardless of whether the person wishing to operate it has a coin of the proper denomination; for example, in selling a newspaper or a magazine selling for ten cents, the release mechanism could be operated by the insertion of a dime, or by the insertion of two five-cent pieces in the machine.

Many types of coin-controlled mechanisms are now in use, and certain coin-controlled slides are also in common use. One of the objects of the present invention is to provide a construction for enabling a common type of coin-receiving means to be employed, constructed for operation by means of coins of different denominations, and to provide simple means for cooperating with the same to enable the release mechanism to be operated either through the medium of a single coin of a higher denomination, or a plurality of coins of a lower denomination.

A further object of the invention when applied to a vending machine, is to provide simple means for preventing the machine from being operated in such a way as to permit the removal of more than a single vended article as a result of the insertion of the price of the article in a coin, or coins.

Further objects of the invention will appear hereinafter.

The invention consists in the novel parts and combination of parts to be described hereinafter, all of which contribute to produce an efficient coin controlled release mechanism.

A preferred embodiment of the invention is described in the following specification, while the

broad scope of the invention is pointed out in the appended claims.

In the drawings:

Fig. 1 is a vertical section through one end of a newspaper vending machine embodying my invention, certain parts being broken away.

Fig. 2 is a horizontal section taken about on the line 2—2 of Fig. 1, certain parts being broken away, and further illustrating details of the mechanism.

Fig. 3 is a vertical section taken about in the plane of the line 3—3 of Fig. 1, and particularly illustrating details of the releasing mechanism for the ejector.

Fig. 4 is also a vertical section but taken about in the plane of the line 4—4 of Fig. 1, and particularly illustrating a check device for preventing a fraudulent operation of the machine, which would enable more than one vended article to be delivered from the machine on a single coin payment.

Fig. 5 is a vertical section taken about on the line 5—5 of Fig. 1, and illustrating a one-way check device which operates in such a way as to prevent a partial actuation of the ejector.

Fig. 6 is a fragmentary vertical section taken through one of the coin-receiving devices, and illustrating how the presence of the coin enables the coin-receiving device to transmit motion to actuate the release mechanism.

Fig. 7 is a perspective of the detent bar, which is one of the novel elements of the machine.

Before proceeding to a more detailed description of the invention, it should be stated that in practicing the invention I construct the mechanism in such a way that the desired release can be effected through the use of a single coin of a high denomination, or a plurality of coins of a lower denomination equal in sum to the value

of the single coin. The principle on which the machine operates is that when a single coin of higher denomination is employed, it enables a detent to be given its complete or full movement immediately, thereby moving it from its position

of rest in which it obstructs the movement of the part that is to be moved, to its releasing position. The mechanism can be used for various purposes; for example, as a lock for a locker door, or closet door, or a drawer, or any situation where a customer is to be provided with an article, or access to space through the medium of coins introduced into the machine. When the coins of smaller denomination are introduced in succession, each operation of the coin-receiving device will effect a partial movement of the de-

tent toward its releasing position. In other words, the mechanism is so constructed that it can be operated by a coin of higher denomination; for example, a dime, and also by the insertion of two five-cent coins requiring two operations of the five-cent coin-receiving device.

Referring more particularly to the specific construction illustrated, and with special reference to Figs. 1 and 2, the mechanism is mounted in a casing 1 of any suitable construction, preferably including a magazine 2 in which the articles 3, such as newspapers to be vended, are received. At one end of the casing a substantially vertical partition wall or frame plate 4 may be provided, on which most of the mechanism of the machine is mounted.

At an elevated point at the front wall 5 of the casing, I mount a plurality of coin-receiving devices. In the present instance, there are only two of these devices, one of which is constructed to be operated by the insertion of a dime, and the other of which is constructed to be operated by the insertion of five-cent pieces, or nickels. These coin-receiving devices 6 and 7 are preferably mounted side by side. Of course, these coin receivers may be adapted to operate on any other denomination of coins. In the present instance, they can be operated with dimes and nickels, because these denominations particularly adapt the machine for selling newspapers or other periodicals that sell for a dime. The coin-receiving devices 6 and 7 are preferably of the common "slide" type; that is to say, each coin receiver is formed with a push slide 8 (see Fig. 6) and guided to slide in a horizontal position in a suitable guide 9. The forward end of each slide 8 presents a pocket in which a coin such as a coin 10 can be inserted, and when the coin has been inserted, by pushing upon the slide 8, drivers indicated generically by the number 11, also in the form of slides guided in the guide 9, can be pushed forwardly. I utilize this forward movement of the two drivers 11a and 11b to operate the releasing mechanism.

These coin-receiving devices 6 and 7 are mounted or so adapted that the slide corresponding to the coin of larger denomination; for example, the slide having the driver 11a, will give the release mechanism twice as much movement as the driver 11b. It is obvious that this could be accomplished by mounting the coin-receiving device 6 in advance of the device 7, or by constructing the actuator cooperating with these drivers in such a way that it will be given half the movement by the driver 11b that would be given to it by the driver 11a. In the present instance, this effect is accomplished by providing the driver 11a with a removable extension or head 12, and mounting the slides in alignment laterally.

Referring now particularly to Fig. 1, the actuator 13 is preferably in the form of a bell crank lever having an upper arm in the path of the head 12, and the driver 11b, and having a lower arm 14 that carries means for actuating the detent that normally prevents movement of the movable part; for example, the ejector of the machine. This bell crank lever 13 is pivotally mounted on the vertical frame plate 4.

The detent that is advanced by movements of the actuator 13, is preferably in the form of a detent bar 15 guided to slide vertically, or in a more or less upright position on the face of the frame plate 4.

Any suitable means may be provided for 75

enabling the actuator 13 to move the detent bar 15, but in the present instance this is accomplished by providing a dog or driving pawl 16 that is pivotally mounted on the end of the arm 14. The pawl 16 projects up from a plate-like body 17, and in the position of rest of the actuator the lower edge of this body 17 is seated on a bracket 18 upon which it is held by any suitable means such as a coil spring 19. When the actuator 13 is operated by the nickel coin-receiving device 7, the driver 11b will strike a transverse plate 20 carried by the upper end of the actuator, and will push the same rearwardly toward but not up to a vertical position indicated by the dotted lines 21; but this movement will move the arm 14 through a small angle equal to about half of the angle between the upper arm of the bell crank lever 13 and the vertical line through its pivot, as indicated in Fig. 1. When this movement occurs, as the arm 14 moves upwardly, the spring 19 will pull the dog or pawl 16 into an actuating notch 22 in the detent bar 15, and further movement of the actuator will advance the bar 15 in an upward direction, raising it to an intermediate but non-releasing position, that is to say, sufficiently to enable latch means to engage a latching notch 23 on the opposite side or edge of the bar 15. This latch means is preferably in the form of a pawl 24 that is pulled toward the bar 15 by a coil spring 25. This latch means will therefore hold the bar 15 in this partial advanced or intermediate position, that is, moved toward its releasing position, but still in a non-releasing position. A second operation of the coin device 7 will give a second movement to the actuator 13, causing the pawl 16 to engage in the second notch 26 just below the notch 22. This second movement of the actuator 13 will advance the detent bar an amount equal to its first advance, enabling the latch pawl 24 to engage in a second latching notch 27. Lifting the detent bar 15 in this way will move it into a position such that it will release the ejector of the machine and permit its operation. Any suitable means may be employed for enabling the detent bar to obstruct the movement of the ejector when the detent bar is in its position of rest, and so as to enable the detent bar to free the ejector in its advanced position. In the present instance, however, in order to accomplish this, I prefer to provide the side of the bar 15 with a clearance notch or gap 28. In the completely advanced position of the detent bar 15, this notch will come into alignment with a dog 29 that is a projection from the face of a slide bar 30 that is connected with the ejector 31 within the magazine 2, and which is operated to eject the newspapers 3. The bar 30 is connected up to the ejector so that when the ejector is operated, this bar 30 moves forward. In the present instance, the machine is provided with an actuating shaft 32 having a rigid arm 33 connected by a link 34 to the under side of the bar 30. The shaft 32, where it passes through the lower part of the magazine, is provided with rigid arms 35 connected by links 36 to the ejector 31 so that when the shaft 32 is rotated the ejector will be moved forward. The construction of the ejector will be described more fully hereinafter. The shaft 32 can be rotated through the agency of a pull rod 37 guided through the forward wall 5 of the machine and provided with a knob 38 at its forward end. The rear end of this pull rod or stem 37 is pivotally attached to the rigid arm or lever 33 carried by

the shaft 32. In the operation of the machine, if a dime is inserted in the coin-receiver 6, instead of inserting two nickels in the coin-receiver 7 as already described, the driver head 12 will move the upper arm of the actuator 13 immediately through an angle such as that indicated by the dotted lines 21. In other words, the movement imparted to the detent bar 15 will carry the lower latching notch 27 up to the level of the point of the latch 24, is one single movement.

The mechanism is provided with means for automatically releasing the latch 24 when the ejector 31 is actuated. For this purpose a laterally projecting pin 40 may be provided on the latch that is in the path of the bracket plate 41 projecting up from the slide bar 30. A return spring in the form of a coil spring 42 may be attached to this bracket plate 41 and to a fixed pin 43 to assist in returning the bar 30 and the ejector 31 to their normal position.

The machine is preferably provided with means for insuring that when an ejecting movement is started, the ejector will be moved forward all the way. In other words, it cannot be given a partial movement and then returned to its starting position. For this purpose I provide a check pawl 44 to cooperate with rack teeth 45 formed on the upper edge of the bar 30. This check pawl 44 is pivoted for free movement, and for this purpose I prefer to mount it on the pin 43. The check pawl has a tapered nose at its lower end, the tip of which lies adjacent to the level of the roots of the teeth 45. In the position of rest of the ejector and the bar 30, the nose of this check pawl lies at a gap 46 or cut-away portion for the upper edge of the bar that is cut down to the level of the roots of the teeth. A spring is provided for enabling this pawl to be deflected in either direction by the rack teeth passing the same, but the pawl will operate to prevent any return movement until the rack has passed completely out of contact with the pawl. At the end of the rack the teeth 45 are also omitted so as to form a gap or cut-away portion 47. When this gap or relief edge at 47 arrives under the pawl at the end of the forward movement of the ejector, the spring on the pawl can pull it back into an upright position, enabling the pawl to swing in the opposite direction on its pivot when the bar 30 is returning to its normal position. In the present instance, the spring for the pawl is in the form of a coil spring 48 attached to the upper end of the pawl and having its upper end attached to the upper end of the guide 49 in which the bar 30 is guided.

In the operation of the machine, the person operating it is instructed to insert the coin in the coin slide, push the coin slide inwardly, and then let go. A spring associated with the coin slide (not illustrated) returns the coin slide to its initial position. However, it might occur to a dishonest person that by not letting go of the coin slide to permit its return, the coin slide would then continue to hold the actuator 13 in a releasing position, that is to say, while the latch 24 is holding the detent bar 15 in its released position, thereby permitting advancing movement of the bar 30. If, under these circumstances, the knob 38 were advanced a short distance insufficient however, to trip the latch pawl 24 with the bracket plate 41, the articles such as the papers 3 in the vending machine could be shoved out through the delivery opening of the machine. In order to prevent this, I prefer to

provide another check device operating in such a way that although it will not interfere with the forward movement of the bar 30, it will operate to prevent a reciprocating movement of the bar 30 with a very slight travel. In other words, this check device supplements the operation of the check pawl 44 but is more in the nature of a positive lock for locking the bar 30 against operation in a fraudulent manner. For this purpose I provide the lower edge of the bar 30 with a recess or notch 50, and adjacent to the location of this notch I provide a guide 51 having a vertical guideway 52 for a locking pawl or bolt 53, the upper end of which is formed with a nose to fit into the notch 50. This locking bolt 53 is provided with a wire stem 54 that extends upwardly from the same, and which is connected to a coil spring 55, the upper end of which is attached to the lower arm 14 of the actuator 13. In the position of rest illustrated in Fig. 1, this spring 55 is not in tension, but as soon as the actuator 13 is actuated, tension will be exerted in this spring to pull the lock 53 up against the lower edge of the bar 30, and hence if the operator of the machine then attempts to pull the knob 38 to operate the ejector, the bolt 53 will immediately be pulled up into the notch 50 and arrest any further movement of the notch, and the ejector and bar 30.

If the lock bolt 53 is of sufficient weight and there is no resistance in its guide 52, it could return by gravity; but in order to prevent any possibility of this not occurring, I prefer to provide a small coil spring 56, the lower end of which is anchored on the outside of the guide 51 and the upper end of which is attached to a pin on the latch bolt running in a slot 57 in the guide (see Fig. 4). It should be understood, however, that the spring 56 is a weak spring, and its force is immediately overcome by building up tension in the spring 55.

The coin-receiving devices 6 and 7 are constructed so that as soon as the slide has been given its full rearward movement, the coin falls out of the coin device and into a coin drawer or receptacle 58.

The case 1 is provided with a removable cover 59, which may be locked in place by means of a lock 60 into which a key may be inserted from above, said lock being provided with a bolt 61 that will project under the edge 62 of the cover opening.

The ejector 31 is in the form of an elongated plate, which may be provided at its rear edge with a downwardly projecting flange 63 to which the return spring 64 in the form of a coil spring is attached. The ejector 31 is in the form of a long plate, the ends of which are received quite loosely in a channel-shaped guide (see Fig. 5). In other words, the guide presents horizontal flanges 65 between which the end of the ejector fits quite loosely, and in such a way as to permit the forward end of the ejector to be tipped upwardly when the ejector is operated. In order to give this mode of operation, I provide a construction whereby the operating links 36 already described, will exert an upward thrust as they move the ejector forward. For this purpose these links 36 incline upwardly in a forward direction as indicated in Fig. 1, their forward ends being attached pivotally to small angle brackets 66. The ejector bar is provided with upwardly inclined sharp teeth 67 preferably in the form of wire teeth. These teeth engage the lowermost paper 3 that is to be vended, and operate to push

it out through a delivery opening 68 in the forward wall 5 of the case. This opening is normally closed by an offset cover 69 that has a hinge connection 70 on the inside. This flat cover 69 is constructed so that it more or less obstructs the delivery opening 68, although it will permit the delivery of the paper through it.

The papers 3 are supported on a shelf or false bottom 71, and this bottom is provided with clearance slots 72 for the ejector teeth 67.

Referring again to Fig. 2, I prefer to construct the driver 11b of the nickel coin slide, in such a way that when desired, the extension or head 12 can be removed from the ten-cent coin device and applied to it. This gives the machine great utility in selling daily papers including Sunday editions, because during week days the head 12 can be attached to the five-cent coin slide. This will enable the five-cent coin slide to operate the machine to deliver a paper. On Sunday, when the editions of the paper sell for ten cents, the head 12 would be located on the dime coin slide as illustrated in Fig. 2. This will enable the machine to be operated either by a ten-cent piece or by two nickels, to deliver a paper.

Referring again to Fig. 1, when the latch means 24 is of the kind illustrated, it is preferable to provide a guide bar 24a. This guide bar lies a short distance from the vertical frame plate 4, and is attached to the vertical frame plate 13.

The case is preferably provided with a glass front, or window 74 (see Fig. 2).

The mode of operation of the entire machine will now be described. Upon insertion of a ten-cent coin in the coin-receiver 6, and pushing its slide 8 inwardly, the driver 11a with the extension 12, will be shoved against the plate or cross head 20 at the upper end of the bell crank lever 13, which operates as an actuator for the detent bar 15. By reason of the presence of the head or extension 12, the actuator 13 will be given a complete movement, and as it rocks, the pawl 16 will swing upwardly and engage the upper notch 22, thereby lifting the detent bar 15 sufficiently to bring the notch 28 in line with the projection or dog 29 on the bar 30. The movement of the bar 30 is then unobstructed, and hence when the knob 38 is pulled, this bar 30 will move forward with the ejector 31, the ejector being actuated through the rock shaft 32 and the arms 35 connecting to the link 42. However, before pulling the knob 38 the coin slide will have been released by the operator. If he does not release it and attempts to operate the machine, the tension in the spring 55 will pull the lock bolt or pawl 53 up against the lower edge of the bar 30, and when the knob 38 is pulled, this lock bolt will spring into the notch 50 and prevent any further movement of the ejector in either direction until the coin slide is released.

As the check bar 30 moves forwardly when the knob 38 is pulled, the teeth 45 will strike the nose of the check pawl 44 and deflect it toward the left. The check pawl will operate to prevent any attempt to reverse the movement of the knob 38 in pulling it out. As soon however, as the teeth 45 have completely passed the check pawl, the spring 48 will pull the pawl back into its normal vertical position while the other gap 47 is under the check pawl. This corresponds to the extreme forward position of the ejector.

If a five-cent coin is inserted in the coin receiver 7 (see Fig. 2) its forward end 11b will

strike the cross head 20, rock the bell-crank 13 and cause the pawl 16 to engage notch 22 and raise the detent bar 15, but the movement imparted will only raise the detent bar 15 to a half-way position with the pawl 24 engaging the notch 23. This forward movement of the slide 8, however, will be sufficient to release the coin, and the slide 8 will then return to its normal position to receive a second five-cent piece. When the slide 8 advances the second time, it will again engage the cross head 20, and this movement will actuate the bell-crank lever 13 to bring the pawl 16 into the notch 26, which will then be held at the former level of the notch 22. This will give the detent bar 15 its complete releasing movement so that the pawl 40 engages the lower notch 27, thereby holding the detent bar 15 with its notch 28 in a position that will permit the dog 29 to pass the bar when the ejector moves forward.

As soon as the knob 38 is released, the springs 64 and 42 will return the ejector, and the bar 30 to their normal positions of rest.

It is understood that the embodiment of the invention described herein is only one of the many embodiments this invention may take, and I do not wish to be limited in the practice of the invention, nor in the claims, to the particular embodiment set forth.

What I claim is:

1. In a coin control for releasing a mechanism having a "moving part," the combination of a movable stop normally disposed in a locking position to prevent movement of the said "moving part," and movable into a releasing position in which it permits movement of said "moving part," a primary coin-receiving means for receiving a coin of a given denomination, a secondary coin-receiving means for receiving a coin of a lower denomination, each coin-receiving means having a driver with means for moving the same through a path of travel, an actuator actuated in common by said drivers and projecting into the paths of said drivers, said drivers having engaging points respectively located at different distances from said actuator so that the driver corresponding to the coin of lower denomination will consume more of its travel than the driver corresponding to the coin of larger denomination before engaging the actuator, means associated with the actuator for moving the stop with a step-by-step movement through the agency of successive operations of the secondary driver to advance the stop into its releasing position; said primary driver operating to impart a complete movement to the actuator to move the stop immediately to its releasing position through the agency of one actuation of the primary driver.

2. In a coin control for releasing a mechanism having a "moving part," the combination of a movable stop normally disposed in a locking position to prevent movement of the said "moving part," and movable into a releasing position in which it permits movement of said "moving part," a primary coin-receiving means for receiving a coin of a given denomination, a secondary coin-receiving means for receiving a coin of a lower denomination, each coin-receiving means having a driver with means for moving the same through a path of travel, an actuator actuated in common by said drivers and projecting into the paths of said drivers, said drivers having engaging points respectively located at different distances from said actuator so that the driver corresponding to the coin of lower denomination will consume

more of its travel than the driver corresponding to the coin of larger denomination before engaging the actuator, means associated with the actuator for moving the stop with a step-by-step movement through the agency of successive operations of the secondary driver to advance the stop into its releasing position; said primary driver operating to impart a complete movement to the actuator to move the stop immediately to its releasing position through the agency of one actuation of the primary driver, and movable means associated with the secondary driver for altering the location of its engaging point so as to enable one operation of the secondary driver to impart a great movement sufficient to move the stop to its releasing position in one actuation of the secondary driver.

3. In a coin control for releasing a mechanism having a "moving part," the combination of a movable stop normally disposed in a locking position to prevent movement of the said "moving part," and movable into a releasing position in which it permits movement of said "moving part," a primary coin-receiving means for receiving a coin of a given denomination, a secondary coin-receiving means for receiving a coin of a lower denomination, each coin-receiving means having a driver with means for moving the same through a path of travel, an actuator actuated in common by said drivers and projecting into the paths of said drivers, said drivers having engaging points respectively located at different distances from said actuator so that the driver corresponding to the coin of lower denomination will consume more of its travel than the driver corresponding to the coin of larger denomination before engaging the actuator, a pawl actuated by the actuator, said stop having a plurality of spaced shoulders to cooperate with said pawl when the actuator is operated, to advance the stop with a step-by-step movement through the agency of successive operations of the secondary driver to move the stop to its releasing position, said primary driver operating to impart a complete movement to the actuator to move the stop immediately to its releasing position through the agency of one actuation of the primary driver.

4. In a coin control for releasing a mechanism having a "moving part," the combination of a primary coin slide having means for receiving a coin of a given denomination, a secondary coin slide having means for receiving a coin of a lower denomination, means for supporting and guiding said slides to move substantially parallel with each other, an actuator disposed to the rear of said coin slides, each of said coin slides having a driver with an engaging tip to impinge upon the actuator during the travel of the driver, a stop bar guided to move longitudinally in a direction transverse to the direction in which said "moving part" moves, said stop bar normally located in a locking position in which it prevents the actuation of said "moving part," and capable of assuming a releasing position in which it permits free movement of said "moving part," a pawl carried by the actuator for shifting the stop-bar toward its releasing position, said stop-bar having spaced shoulders to cooperate with said pawl, the engaging tips of said drivers being located at different distances from the actuator with the engaging tip of the primary driver located nearer to the actuator than that of the secondary driver, said secondary driver operating when actuated successively, to advance the stop-bar with a step-by-step movement to its

releasing position, and said primary driver operating upon one actuation of the same to impart sufficient movement to the actuator to move the stop-bar in one operation to its releasing position.

5. In a coin control for releasing an ejector slide for a vending machine, the combination of a primary coin slide and a secondary coin slide mounted and guided to slide in a direction substantially parallel with the direction of movement of the ejector slide, said primary coin slide having means for receiving a coin of a given denomination, said secondary coin slide having means for receiving a coin of a lower denomination, an actuator disposed to the rear of said coin slides, each of said coin slides having a driver with an engaging tip to impinge upon the actuator during the travel of the driver, a stop-bar guided to move longitudinally in a direction transverse to the direction in which said coin slides move and normally located in a locking position in which it prevents the actuation of the ejector slide, said stop-bar capable of moving into a releasing position in which it will permit actuation of the ejector slide, and a pawl carried by the actuator for shifting the stop-bar to its releasing position.

6. In a coin control for releasing a mechanism having a "moving part," the combination of a movable stop normally disposed in a locking position to prevent movement of the said "moving part" and movable into a releasing position in which it permits movement of said "moving part," a coin-receiving means having a driver associated therewith and movable through a path of travel when the coin-receiving means is operated, an actuator disposed in the path of travel of the driver impinged upon by the driver and moved thereby, and means actuated by the actuator for moving the stop with a step-by-step movement to its releasing position.

7. In a coin control for releasing a mechanism having a "moving part," the combination of a movable stop normally disposed in a locking position to prevent movement of the said "moving part" and movable into a releasing position in which it permits movement of said "moving part," a coin-receiving means, an actuator disposed to the rear of said coin-receiving means, said coin-receiving means having a driver, and means for actuating the driver so that it impinges upon the actuator during the travel of the driver, a movable stop, means associated with the actuator for moving the movable stop with a step-by-step movement to move the same into its releasing position, and a detachable head carried by the driver for increasing the amount of movement that can be imparted by the driver to the actuator, and operating to give the same sufficient movement to move the movable stop by a single actuation, to its releasing position.

8. In a coin control for releasing an ejector slide for a vending machine, the combination of a primary coin slide and a secondary coin slide mounted and guided to slide in a direction substantially parallel with the direction of movement of the ejector slide, said primary coin slide having means for receiving a coin of a given denomination, said secondary coin slide having means for receiving a coin of a lower denomination, an actuator disposed to the rear of said coin slides, each of said coin slides having a driver with an engaging tip to impinge upon the actuator during the travel of the driver, a stop bar guided to move longitudinally in a direction

transverse to the direction in which said coin slides move and normally located in a locking position in which it prevents the actuation of the ejector slide, said stop bar capable of moving into a releasing position in which it will permit actuation of the ejector slide, a pawl carried by the actuator for shifting the stop bar to its re-

leasing position, and an extension head attachable to, and detachable from, the secondary driver, operating when attached to the same to enable the secondary driver to move the stop bar to its releasing position in one operation of the secondary driver.

GEORGE W. DOOLEY.
